UNITED STATES PATENT OFFICE.

HAROLD CHARLES WATERER, OF SOUTHALL, ENGLAND, ASSIGNOR TO LEONARD PATRICK DRISCOLL, OF EALING, LONDON, ENGLAND.

STEADYING DEVICE FOR LATHES.

1,419,786.

Specification of Letters Patent. Patented June 13, 1922.

Application filed September 14, 1920. Serial No. 410,113.

To all whom it may concern:

Be it known that I, HAROLD CHARLES WATERER, a subject of the King of Great Britain and Ireland, residing at 165 Townsend Road, Southall, Middlesex, England, have invented certain new and useful Improvements in Steadying Devices for Lathes, of which the following is a specification.

My invention relates to lathes.

10 My invention has for its object to provide an improved device which enables the material being operated upon in the lathe to be steadied in an efficient manner and which at the same time reduces the frictional resistance involved in the steadyng operation to a minimum.

My invention consists in a device of the type indicated in which the material is steadied by being gripped in a sleeve mounted on ball or like anti-friction bearings which are disposed in a housing adapted to be clamped to the lathe-bed.

20 My invention further consists in the improved steadyng device for lathes to be hereinafter described.

Referring now to the accompanying drawings which illustrate my invention and form part of my specification,

Figure 1 shows an elevation of a device 30 constructed according to my invention, while,

Figure 2 shows a vertical section on the line A—A on Figure 2.

In carrying my invention into effect according to one form I construct a housing 35 formed of an annular portion, 1, provided with a base, 2, which rests on the lathe-bed, 3. The housing is clamped to the lathe-bed in the desired position by means of the bolt, 40 4, and the plate, 17.

In the annular portion, 1, three holes, 5, equidistant from one another are formed which give access to the adjusting screws, 6, for gripping the material being operated 45 upon in the lathe.

An annular recess, 7, is formed in the housing to accommodate the projecting ends of the screws, 6.

The screws, 6, of which there three in 50 number, engage with threaded holes, 8, equally spaced on the rotatable sleeve, 9. These screws are provided with squared recesses, 10, in their outer ends so that they may be adjusted in position radially by

means of the chuck-key, 11, to suit the size 55 of the material being operated upon.

The sleeve, 9, is provided with grooves, 12, which co-operate with grooves, 13, on the stationary members, 14, to form ball-races for the balls, 15, flanges, 16, are formed on 60 the stationary members, 14.

Grooves, 18 and 19, are formed on the member, 14 and sleeve, 9, respectively for introducing the balls into the ball-races, the position of these grooves being preferably 65 such that they are out of register with one another when the screws, 6, register with the holes, 5.

The device is assembled by forcing the members, 14, into the bore of the annular 70 portion, 1, of the housing and assembling the sleeve, 9, therewith so that the grooves, 12 and 13, register with one another and the groove, 18, registers with the groove, 19. The balls are then introduced into the ball-races through the latter set of grooves.

The device when set up on the lathe-bed has the axis of rotation of the sleeve, 9, coincident with the rotational axis of the material being operated upon.

80 When it is desired to steady material, such for example as a round steel bar, the bar is threaded through the sleeve, 9, and mounted as required on the lathe. The screws, 6, are then adjusted to firmly grip the bar so that 85 when the lathe is in operation the ball bearings of the device act to steady the bar.

By means of my invention it will be seen that material being operated upon in a lathe may be steadied in an exceedingly efficient 90 manner and with the minimum amount of frictional resistance. Also the construction of the device allows a wide range of sizes of material to be accommodated, while, the absence of projecting rotating parts obviates accidents to the machinists.

I wish it to be understood that the above example of my invention is simply to be regarded as typical only and not as in any way restricting my invention thereto as 100 modifications may be made therein without departing beyond the scope of my invention.

What I claim is:

1. In a device for steadyng material being 105 operated upon in a lathe, a housing, a rotatable member in said housing, said housing and rotatable member having coacting longi-

tudinally spaced bearings, an intermediate non-bearing zone, and means for gripping the material disposed in said rotatable member, said means being located in said non-bearing zone.

2. In a device for steadyng material being operated upon in a lathe, the combination of a housing, a rotatable member in said housing, a plurality of longitudinally spaced anti-friction bearing sets operatively disposed between said housing and rotatable member together with means for gripping material disposed in said rotatable member and located between said anti-friction bearing sets, 15 as set forth.

3. In a device for steadyng material being operated upon in a lathe the combination of a housing, a rotatable member in said housing, a plurality of longitudinally spaced ball bearing sets operatively disposed between said housing and rotatable member together with means for gripping material disposed in said rotatable member and located between said ball bearing sets, as set 20 forth.

4. In a device for steadyng material being operated upon in a lathe, the combination of a housing, a rotatable member in said housing, said housing and rotatable member having longitudinally spaced bearings providing an intermediate non-bearing zone, together with adjustable means for gripping material disposed in said rotatable member and located in said non-bearing zone.

35 5. In a device for steadyng material being operated upon in a lathe, the combination of a housing, a rotatable member in said housing, a plurality of longitudinally spaced anti-friction bearing sets operatively disposed between said housing and rotatable member and providing a non-bearing zone between them, together with adjustable means for gripping material disposed in said rotatable member and located between said 40 anti-friction bearing sets and in said non-bearing zone.

6. In a device for steadyng material being operated upon in a lathe, the combination of a housing, a rotatable member in said housing, a plurality of longitudinally spaced ball bearing sets operatively disposed between said housing and rotatable member and providing a non-bearing zone between them, together with adjustable means for gripping material disposed in said rotatable member and located between said ball bearing sets and in said non-bearing zone.

55 7. In a device for steadyng material being operated upon in a lathe, a housing, a rotatable member in said housing, said housing and rotatable member having longitudinally spaced bearings and an intermediate non-bearing zone together with adjustable screwed means for gripping the material disposed in said rotatable member and located

between said bearings and in said non-bearing zone.

8. In a device for steadyng material being operated upon in a lathe, the combination of a housing, a rotatable member in said housing, a plurality of longitudinally spaced anti-friction bearing sets operatively disposed between said housing and rotatable member and providing an intermediate non-bearing zone together with adjustable 70 screwed means for gripping material disposed in said rotatable member and located between said anti-friction bearing sets and in said non-bearing zone.

9. In a device for steadyng material being operated upon in a lathe the combination of a housing, a rotatable member in said housing, a plurality of longitudinally spaced ball bearing sets operatively disposed between said housing and rotatable member 85 and providing an intermediate non-bearing zone together with adjustable screwed means for gripping material disposed in said rotatable member and located between said ball bearing sets and in said non-bearing 90 zone.

10. In a device for steadyng material being operated upon in a lathe, the combination of a housing having spaced peripheral holes, grooved flanged rings in said housing, 95 a rotatable member having spaced grooves thereon co-acting with said first mentioned grooves, anti-friction bearing members in said grooves, a plurality of adjusting screws in said rotatable member together with 100 means for securing said housing to a lathebed, as set forth.

11. In a device for steadyng material being operated upon in a lathe, the combination of a housing having peripherally spaced 105 holes, a rotatable member in said housing, said housing and rotatable member having co-acting longitudinally spaced bearings together with means for gripping the material disposed in said rotatable member 110 and operable through said holes in said housing, as set forth.

12. In a device for steadyng material being operated upon in a lathe, the combination of a housing having peripherally 115 spaced holes, a rotatable member in said housing, a plurality of longitudinally spaced anti-friction bearing sets operatively disposed between said housing and rotatable member together with means for gripping 120 the material disposed in said rotatable member, said gripping means being located between said anti-friction sets and operable through said holes in said housing, as set forth.

13. In a device for steadyng material being operated upon in a lathe, the combination of a housing having peripherally spaced holes, a rotatable member in said housing, a plurality of longitudinally spaced ball 130

- bearing sets operatively disposed between said housing and said rotatable member together with means for gripping the material disposed in said rotatable member, 5 said gripping means being located between said ball bearing sets and operable through said holes in said housing, as set forth.
14. In a device for steadyng material being operated upon in a lathe, the combination of a housing having peripherally spaced holes, a rotatable member in said housing, said housing and rotatable member having co-acting longitudinally spaced bearings together with screwed means for gripping the 10 material disposed in said rotatable member, said screwed means being located between said bearings and operable through said holes in said housing, as set forth.
15. In a device for steadyng material being operated upon in a lathe, the combination of a housing having peripherally spaced holes, a rotatable member in said housing, a plurality of longitudinally spaced anti- 15
- friction bearing sets disposed between said housing and said rotatable member together 25 with screwed means for gripping the material disposed in said rotatable member said screwed means being located between said bearings and operable through said holes in said housing, as set forth. 30
16. In a device for steadyng material being operated upon in a lathe, the combination of a housing having peripherally spaced holes, a rotatable member in said housing, a plurality of longitudinally spaced ball 35 bearing sets operatively disposed between said housing and rotatable member, together with screwed means for gripping the material disposed in said rotatable member, said screwed means being located between 40 said bearings and operable through said holes in said housing, as set forth.

In testimony whereof I have signed my name to this specification.

HAROLD CHARLES WATERER.
